UNITED STATES PATENT OFFICE.

HAKULYO C. TANABE, OF MARYSVILLE, CALIFORNIA.

TOY.

1,118,826.

Specification of Letters Patent. Patented Nov. 24, 1914.

Application filed November 29, 1913. Serial No. 803,775.

To all whom it may concern:

Be it known that I, HAKULYO C. TANABE, a citizen of Japan, residing at Marysville, in the county of Yuba and State of California, have invented new and useful Improvements in Toys, of which the following is a specification.

This invention relates to toys, and particularly to aerial toys; and it has for its primary object the provision of a device of this character which will include a revolving head provided with vanes set angularly and with such regard to each other as to cause the head to rise for a considerable distance in the air when released from the projecting device, and further the provision of such form of projecting device wherein the head may be readily released and in a way which will minimize the possibility of one being injured during the operation of using the toy.

With the above and other objects in view, the invention consists of certain novel features of construction, combination and arrangement of parts, as will be hereinafter described and claimed:

In the accompanying drawings:—Figure 1 is a perspective view of the toy; Fig. 2 is a vertical section therethrough; Fig. 3 is a horizontal section, taken through the spindle at a point above the ratchet disk; and Fig. 4 is a perspective view of the projecting means.

The toy comprises a spindle 1 preferably formed of wood and provided at its upper end with a head 2 having a plurality of angularly disposed vanes 3, which are set with proper regard to each other, whereby the head when revolved in one direction will be projected for a considerable distance into the air. The spindle is provided at a suitable point in its length with a metallic disk 4 having an inner circular series of openings 5 and an outer concentric series of ratchet openings 6. The metal from which the disk 4 is formed is upstruck or otherwise suitably formed above the opening 6 to provide guiding surfaces 7 for a purpose to be hereinafter fully explained. The disk 4, while being arranged in the present instance at a point directly beneath the head 2 may be obviously placed at any desired point in the length of the spindle 1 as may be deemed advisable toward properly balancing the structure while in flight.

The projecting mechanism by means of which the head 2 may be projected for a considerable distance into the air comprises a body 8 having a central opening 9, in which is arranged a coil spring 10. This spring has one of its convolutions 11 extended beneath the body 8 and terminally secured thereto by a suitable fastening 11, while the opposite convolution 12 of the spring is extended above the upper face of the body 8 and terminally formed into a hook which is adapted to engage in any one of the openings 5 of the disk 4 on applying the head to the body. The said body is provided with a yieldable projection or dog 13, which is adapted to be successively engaged in the openings 5, hence the provision of the guiding surfaces 7. These guiding surfaces are adapted to cause a slight relative separation of the body 8 and the head 2 when the latter is rotated on the former for the purpose of bringing the spring under the necessary tension.

The length of the spindle 1 is such that when it is extended through the center passage in the body 8 the major portion of the spindle will project below the head and, as a consequence thereof, pressure of the hand may be applied thereto as to cause the lug or dog 13 to be released from the adjacent ratchet opening 6. At this time the spring will tend to assume its normal condition and in so doing the head 2 will be consequently rotated and projected into the air. The approximate distance that the head 2 may be projected into the air obviously depends upon the tension under which the mentioned spring is brought by rotating the head upon the body 8, as previously described.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention as claimed.

I claim:—

A toy comprising a member having a central opening, a coiled spring mounted in the opening and having one of its ends secured to the body and having its other end free therefrom and provided with a hook, a

105

110

spindle removably extending through the opening and provided at one end with a plurality of angularly disposed vanes, a head carried by the spindle and rotatably associated with the body member and provided with an opening to receive the hooked end of the spring and also provided with a second opening and an inclined arm presenting a guiding surface above said opening, and a

yieldable dog projecting from the member 10 and to engage said second opening.

In testimony whereof I affix my signature in presence of two witnesses.

HAKULYO C. TANABE.
